Primary Examiner — Karen E Kearney*Assistant Examiner* — Carissa C Fitts(74) *Attorney, Agent, or Firm* — Design IP(57) **CLAIM**

The ornamental design for a lighting device, as shown and described.

DESCRIPTION

FIG. 1 is a front perspective view of a lighting device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a front perspective view thereof, with a portion of the lighting device in an alternate configuration.

The dashed broken lines in FIGS. 1-7 show unclaimed portions of the lighting device. The dashed-dotted broken lines in FIGS. 1-7 show unclaimed boundaries between claimed and unclaimed subject matter. The oblique line shading in FIGS. 1-3 and 7 show a translucent or transparent material. The remaining line shading in FIGS. 1-7 show surface contours, not surface ornamentation. The bottom view is omitted and forms no part of the claimed design.
